(57) **CLAIM**

The ornamental design for a drumstick pet treat, as shown and described.

DESCRIPTION

FIG. 1 is a top perspective view of a drumstick pet treat, according to a new design;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a back view thereof.

The dashed broken lines in the Figures show portions of the drumstick pet treat that form no part of the claimed design. The dot-dashed broken lines in the Figures show boundaries that form no part of the claimed design.

1 Claim, 4 Drawing Sheets
